UNITED STATES PATENT OFFICE.

AXEL PERSON, OF ATTLEBORO, MASSACHUSETTS, ASSIGNOR TO HARVEY CLAP CO., OF ATTLEBORO, MASSACHUSETTS, A PARTNERSHIP.

BRACELET CONSTRUCTION.

Application filed July 11, 1925. Serial No. 42,897.

This invention relates to bracelet construction. One of the objects thereof is to provide a device of the above nature of simple and practical construction and adapted to meet the requirements of use in a highly satisfactory manner. Another object is to provide a bracelet construction which is comfortably worn and which at all times presents an attractive and uniform appearance. Another object is to provide a flexible link bracelet construction wherein the component links are dependably joined together and yet capable of convenient removal or renewal for adjustment of the length of the bracelet or for repair. Another object is to provide a construction of the above nature which is strong and durable. Other objects will be in part obvious or in part pointed out hereinafter.

The invention accordingly consists in the features of construction, combinations of elements, and arrangements of parts as will be exemplified in the structure to be herein-after described and the scope of the application of which will be indicated in the following claims.

In the accompanying drawing, in which is shown one of the various possible embodiments of this invention,

Figure 1 is a side elevation showing a portion of a bracelet;

Figure 2 is a vertical section through the construction shown in Fig. 1;

Figures 3, 4 and 5 are sections taken substantially along the lines 3—3, 4—4 and 5—5 respectively of Fig. 2;

Figure 6 is a top plan view showing the parts in normal position;

Figure 7 is a view similar to Fig. 6 showing the parts in extended position;

Figure 8 is a side elevation of Fig. 7, and

Figure 9 shows a pair of adjoining links positioned for separation or joining.

Similar reference characters refer to similar parts throughout the several views of the drawing.

Referring now to the drawing in detail, there is shown in Figure 1 three links 10 of a bracket chain. These links are hollow, as shown in Figures 2 and 3, each comprising preferably a top wall 11, vertical side walls 12 and 13, and a bottom wall 14. Preferably, as shown in Figure 3, the top wall 11 and the side walls 12 and 13 are formed of one piece of metal and the bottom wall 14 is

a separate part held in place by flanged-over portions 12^a and 13^a of the side walls. The side edges of the base member 14 are preferably undercut to accommodate the flanged portions 12^a and 13^a, so that the link is provided with a smooth, even surface adapted to rest upon the wrist of the wearer.

Inside of each of these hollow links 10 is a connecting member or link 15 which is slideable longitudinally within the link 10. As viewed in Figure 2, the right-hand end of the connecting link 15 is provided with a depending wall or flange 16, and the left-hand end of the base member 14 is flanged upwardly providing an end flange or wall 17. Between these flanges 16 and 17 is interposed a spiral compression spring 18 which thus constantly urges the connecting link 15 toward the right. This spring 18 is preferably made oval in cross-section, as may be seen from Figure 3, as is best suited to the rectangular space which it occupies.

Still referring to Figure 2, the left-hand end of the connecting link 15 projects from the left-hand end of the link 10, and is provided with a downwardly hooked end 20 which passes over and engages a transversely extending member 21 of the adjoining link 10. Each of the links 10 is provided adjacent its right-hand end with one of these transversely extending members 21 which preferably take the form of pins, circular in cross-section, extending between and secured in the side walls 12 and 13. The spring 18 thus acting through the connecting link 15 and its connection with the adjoining link 10 draws the two adjoining links yielding together, the ends of their upper surfaces 11 abutting, as is shown in Figures 1, 2 and 6.

The tops of the links 10 are preferably engraved or otherwise provided with a suitable design, as is shown in Figure 6. The top surfaces of the connecting links 15 are also preferably provided with a corresponding design. Thus, when the bracelet is stretched, as shown in Figure 7, compressing the springs 18, the connecting links 15 fill the gaps between adjacent links 10 and, being suitably engraved, preserve the continuity of appearance of the bracelet. When the bracelet is stretched or expanded, no unsightly gaps appear.

The connecting links 15 are provided with depending side walls or flanges 22 and 23,

which differ in height from the side walls 12 and 13 of the links 10 substantially only by the combined thicknesses of the parts 11 and 14. This is of distinct advantage when the bracelet is stretched or expanded as shown in Figures 7 and 8. The side walls 22 and 23 preserve the continuity of appearance of the bracelet from the side and assist in giving the bracelet the appearance of being made up of solid members. These side flanges or walls 22 and 23 also lend to the strength and smoothness of operation of the structure.

The end flange 17 of the base member 14 is suitably spaced from the side walls 12 and 13, as indicated in Figures 3 and 4, to accommodate these flanges 22 and 23. Thus, it will be seen that when the bracelet is stretched, the continuity of appearance is maintained both upon the top and upon the sides of the bracelet.

As has been described above, the links 10 are pivotally connected by the hooked portions 20 of the connecting links 15 engaging with the pins 21. In addition, the side walls 12 and 13 of the links are preferably shaped at their ends to interfit along rounded surfaces and thereby add to the smoothness of operation of the connecting links. Preferably the right-hand ends of the walls 12 and 13 are provided with rounded projections 12^b and 13^b projecting beyond the end of the top surface 11. Through these projecting parts 12^b and 13^b are passed the pins 21, the pins preferably being headed-over, as indicated at 21^a, at each end. The left-hand ends of the wall 12 and 13 are undercut in rounded fashion to mate with the rounded edges of the projections 12^a and 13^a. In this manner an attractive appearance and at the same time a smoothly operating connection are had. In order to further add to the smooth appearance of the bracelet and to avoid any edges which might come into engagement with the wrist of the wearer, the right-hand ends of the base members 14 of the links 10 are curved upwardly, as shown at 14^a in Figure 2. These parts 14^a are curved upwardly preferably to engage the pins 21 and substantially close the ends of the hollow links beneath the pins. They thus prevent dust or moisture from the skin from working its way into the hollow links.

The component links 10, each with its connecting link 15 therein, constructed and joined as has been described, are conveniently separable and independently removable from the bracelet to vary the length of the bracelet or for purposes of repair or replacement. Figure 9 represents the manner in which these links are separated. Two adjoining links are first pulled apart, compressing the spring 18 and exposing the connecting link 23, as shown in Figure 8. The

two links are then swung about the pivot pin 21 to an angle with each other substantially as shown in Figure 9, the connecting link 15 being held distended and the spring 18 under compression. The parts being held as shown in Figure 9 the two links 10 may be separated by simply sliding the hooked end 20 outwardly and upwardly from engagement with the pin 21. Similarly the links may again be connected as desired. Thus, if it is desired to shorten the bracelet, any desired number of links with their associated connecting links 15 may be bodily removed. The removal may be of the end links or of any desired intermediate links. If it be desired to lengthen the bracelet, any desired number of links may conveniently be inserted.

From the foregoing, it will be seen that there is herein provided a bracelet construction which attains many important practical advantages. The structure under all conditions of use is attractive and substantially uniform in appearance, and in addition is constructed to rest comfortably upon the wrist of the wearer. The bracelet is made strong and durable and the component parts thereof are assembled in the most convenient and simple manner.

As many possible embodiments may be made of the above invention, and as many changes might be made in the embodiment above set forth, it is understood that all matter hereinbefore set forth or shown in the accompanying drawing is to be interpreted as illustrative and not in a limiting sense.

I claim as my invention:

1. In a detachable link bracelet construction, in combination, a series of outer box links each having a top wall, a bottom wall, vertical side walls, a transverse pin extending between said side walls adjacent one end thereof and at the other end an end flange projecting upwardly from said bottom wall, an inner link within each of said box links, each of said inner links having a top wall, vertical side walls and at one end thereof an end wall extending between said side walls, at the other end thereof said top wall being extended beyond said side walls and curved downwardly in the shape of a hook, each of said inner links being slidable longitudinally in its box link, said end flanges of said box links being spaced from the side walls thereof to permit the side walls of said inner links to slide therebetween, and a compression spring within each of said box links acting between the end flange thereof and the end wall of the inner link therein, and said hooked end of each of said inner links being removably hooked over the transverse pin of a next adjoining box link.

2. In a detachable link bracelet construction, in combination, a series of box links

arranged end to end, means connecting said box links to form a flexible chain of substantially continuous outer appearance, said connecting means between two adjacent box links comprising a connecting link slidable longitudinally within one of the box links and urged thereinto by spring means, said connecting link having a top wall and vertical side walls, said top wall being extended 5 at one end beyond said side walls and being curved downwardly in the shape of a hook, 10

and a transverse pin extending between the side walls of the adjacent box link near one end thereof, said hook detachably engaging said transverse pin and the adjacent end of 15 the bottom wall of said box link being curved upwardly toward said pin.

In testimony whereof, I have signed my name to this specification this eighth day of July, A. D. 1925.

AXEL PERSON.
